COOKING STOVE OR RANGE.

No. 17,071.

Patented Jan. 18, 1887.

UNITED STATES PATENT OFFICE.

GEORGE E. WILBUR, OF TAUNTON, MASSACHUSETTS.

DESIGN FOR A COOKING STOVE OR RANGE.

SPECIFICATION forming part of Design No. 17,071, dated January 18, 1887.

Application filed August 10, 1885. Serial No. 174,074. Term of patent 14 years.

To all whom it may concern:

Be it known that I, GEORGE E. WILBUR, of Taunton, in the county of Bristol and State of Massachusetts, a citizen of the United States, have invented a new and useful Design for Cooking Stoves and Ranges, of which the following is a full, clear, and exact description, reference being had to the accompanying photographs, forming a part of this specification, 10 in describing the same.

The photograph marked *a* is a view of the front of the stove, and that marked *b* is a view of the side at the left of the front.

The design consists of two especial features— 15 namely, the open or basket work, which is common to the cabinet-base and to the elevated shelf and its support, and the rosettes, which form the prominent features of the various panels and doors, and which are found in 20 more or less pronounced form in various other parts of the stove.

Referring to the photographs, *A* represents the stove-legs; *B*, the cabinet-base, which is made up of the molding *c*, having extending 25 downward therefrom at the corners the sections *c'*, in which will be found the rosette-sections *c''* about the panels *c''*. Above the molding are the side sections, *c'*, having a basket-work pattern of peculiar character, as represented in the photographs, and the corner-sections *c''*. These parts already described make 30 up the cabinet-base. Above this there are four principal ornamental pieces. The first and principal one is the oven-door *D*. This, 35 it will be observed, has the rosettes *d* arranged at each corner, the upper and lower panels, *d'*, and the name-plate *d''*. Next in order of prominence is the ash-pit door *E*. Here the rosettes *e* are not arranged at the corners, but centrally 40 upon the upper and lower portion thereof, and between them is the plain panel *e'*, and upon either side are the moldings *e''*, which are in turn inclosed by the side and top and bottom edges, *e''*.

45 The plate *F* is the next section which contains the essential features of the design, and in this plate it will be seen that the rosettes *f* bear still a different relation to the panel *f'*. The side ash-pit door, *G*, is well shown in the 50 photograph *b*, and has the side rosette-sec-

tions, *h*, and the intermediate panel, *h'*. The support for the elevated shelf combines the rosette-sections *m*, the basket-work *m'*, such as is found in the base, and the design, as shown, in the shelf, and the box which surrounds the escape-port also bears the rosettes *m''*, arranged at the corners, as represented, and a plain interposed panel, *m''*. The back of the elevated shelf *m'* is made up of the basket-work *m''* and the open-work section *m''*. 55

60 It will be seen that the especial features of the design are the open or basket work of peculiar pattern and the rosettes of peculiar form and arrangement, and that they are used either separately or combined.

65 It will be seen that the basket-work on the cabinet-base, and also of the stove-shelf, bracket or support, and stove-shelf back, is of a peculiar form, in that the bars intersect each other, and also in that every other joint or 70 point of intersection has a rounded projection.

Having thus fully described my invention, I claim and desire to secure by Letters Patent of the United States—

1. In a design for a stove, the cabinet-base 75 having the open or basket work section *c'*, made of intersecting bars, the alternate intersecting points of which are rounded, as shown and described.

2. In a design for a stove, the cabinet-base 80 having the rounded corners *c''*, the downwardly-extending corner-sections *c'*, ornamented with the rosettes *c''*, and the open or basket work sides *c'*, as shown and described.

3. In a design for a stove, the oven-door 85 having the central name-plate, the smooth panels above and below the same, and the square rosettes at the corners of the stove, which are in part covered by the name-plate, as shown and described.

4. In a design for a stove, the support for a stove-shelf, comprising, essentially, the open or basket work *m'*, the bars of which intersect each other and have rounded projections at alternate points of intersection, as shown and 95 described.

5. In a design for a stove, a stove-shelf back of basket or open work, in two forms: first, the plain central section of flat intersecting bars, and, second, the end sections of rounded 100

intersecting bars, the points of intersection being provided with rounded extensions, as shown and described.

6. The design for a cooking stove or range the distinctive features of which are the open-work or basket-work pattern or design of the cabinet-base and the stove-shelf and bracket,

and the rosettes of the stove legs, doors, and panels, and stove-shelf bracket, shown and described.

GEO. E. WILBUR.
